DESIGN FOR A COMBINED DIAL AND HANDS FOR A WATCH OR SIMILAR ARTICLE

John P. V. Heinmuller, Katonah, N. Y., assignor
to Longines-Wittnauer Watch Co. Inc., New
York, N. Y., a corporation of New York

Application January 1, 1942, Serial No. 104,963

Term of patent 14 years

To all whom it may concern:

Be it known that I, John P. V. Heinmuller, a citizen of the United States, residing at Katonah, county of Westchester, and State of New York, have invented a new, original, and ornamental Design for a Combined Dial and Hands for a Watch or Similar Article, of which the following is a specification, reference being had to the accompanying drawing, forming a part thereof.

Fig. 1 is a plan view of a combined dial and hands for a watch or similar article showing my new design.

Fig. 2 is an edge view thereof.

I claim:

The ornamental design for a combined dial and hands for a watch or similar article, as shown.

JOHN P. V. HEINMULLER.
